Design No 388.

Samuel A House

Box Stove Design

Patented 24. June 1857.

UNITED STATES PATENT OFFICE.

SAMUEL A. HOUSE, OF MECHANICSVILLE, NEW YORK.

DESIGN FOR A STOVE.

Specification forming part of Design No. 388, dated June 24, 1851.

To all whom it may concern:

Be it known that I, SAMUEL A. HOUSE, of Mechanicsville, in the county of Saratoga and State of New York, have invented or produced a new Design of Box-Stove; and I do hereby declare that the following is a full and exact description of the same, reference being had to the isometrical perspective drawing of the same, making a part of this specification.

The ornamental design of my stove consists of arabesque figures *a a*, ornaments *b b*, disposed on the moldings and panels, as repre-

sented, and the arrangement and configuration of moldings combined, forming panels and recesses, as represented.

What I claim as new, and desire to secure by Letters Patent, is—

The design and configuration of box-stove substantially the same as herein described and represented.

SAMUEL A. HOUSE.
